UNITED STATES PATENT OFFICE

GEORGE E. HULSE, OF NEW HAVEN, CONNECTICUT, ASSIGNOR TO THE SAFETY CAR HEATING & LIGHTING COMPANY, A CORPORATION OF NEW JERSEY

SUPPORTING FIXTURE

Application filed July 14, 1927. Serial No. 205,599.

This invention relates to supporting fixtures adapted, for example, for supporting from a ceiling an electric lighting fixture or electric fan or the like.

5 One of the objects of the invention is to provide a device of the above nature which is practical and thoroughly efficient. Another object is to provide a device of the above nature which is simple in construction and inexpensive. Another object is to provide a 10 device of the above nature which is convenient to mount or assemble and convenient to take down. Another object is to provide a device of the above nature having convenient provision for the passage of wiring 15 to supply electric current to the apparatus which may be supported thereby. Another object is to provide a device of the above nature which permits the supported apparatus to hang vertically regardless of irregularities or inclination of the ceiling or other overhead structure to which the fixture is secured. Other objects will be in part obvious 20 or in part pointed out hereinafter.

25 The invention accordingly consists in the features of construction, combinations of elements, and arrangements of parts as will be exemplified in the structure to be hereinafter described and the scope of the application 30 of which will be indicated in the following claims.

In the accompanying drawing in which is shown one of the various possible embodiments of this invention,

35 Figure 1 is a top plan view with parts broken away;

Figure 2 is a side elevation;

Figure 3 is a section taken substantially along the line 3—3 of Figure 1, and

40 Figure 4 is a bottom view.

Similar reference characters refer to similar parts throughout the several views of the drawing.

Referring now to the drawing in detail, 45 there is shown a member 10 which is in some- what the form of a plate, having a plurality of spaced outwardly projecting parts shown herein as three in number, 10^a, 10^b and 10^c. This member 10 is adapted to be secured to 50 a ceiling or to an electric outlet box positioned

in the ceiling. For purposes of attaching to an outlet, the member 10 is provided with a central threaded opening 11 by means of which it may be threaded upon the projecting threaded stud of the box. When such a stud 55 is not available the member 10 is secured to the ceiling or other over-head construction by means of screws for which there are provided holes 12 through the parts 10^a, 10^b and 10^c.

The member 10 is shown herein as substantially circular in shape. About its periphery it is provided with downwardly projecting annular means taking the form of three arms 13, 14 and 15 depending from the outer ends 60 of the parts 10^a, 10^b and 10^c respectively. The arms 13, 14 and 15 are each shaped to provide a ledge or upwardly facing supporting surface. As shown herein the arms are provided at their lower ends with laterally 65 projecting extensions or lugs 13^a, 14^a and 15^a respectively which, looking downwardly upon the member 10 as viewed in Figure 1, appear between the spaced parts 10^a, 10^b and 10^c.

70 Fitting within the annular means provided by the arms 13, 14 and 15 and their projecting portions or lugs 13^a, 14^a and 15^a, is a member 16 which is preferably substantially cup shaped. This member 16 is provided adjacent its upper edge with three outwardly projecting arms or lugs 17, 18 and 19. These lugs 75 17, 18 and 19 rest upon the upper surfaces of the parts 13^a, 14^a and 15^a and the cup-shaped member 16 is thereby supported from the 80 member 10.

85 The inner walls of the cup-shaped member 16 are rounded in substantially spherical fashion at the bottom portion, and in the bottom of the cup-shaped member is an opening 90 20. Within the part 16 is a member 21 which has a rounded outer surface mating with the rounded inner walls of the part 16. The member 21 rests loosely within the cup-shaped member 16 and is provided with a threaded opening 22 into which is threaded a supporting member such as a pipe 23. The pipe 23 is adapted to support at its lower end a lighting fixture or an electric fan or any other mechanism which it is desired to suspend from the 95 100

ceiling. The supporting pipe 23 may be of any desired length.

In mounting this supporting fixture, the parts 16 and 21 are separated from the member 10. The member 10 is then secured in position against the ceiling by being threaded upon the projecting stud of the outlet box or fastened by means of screws through the openings 12. When the member 10 is threaded upon an outlet box, a locking screw 24 is employed to lock the member against unthreading. The member 10 having been secured in position, the member 16 is slipped over the supporting pipe 23 and thereupon the member 21 is threaded upon the pipe, the pipe being preferably riveted over as shown at 25 to prevent unthreading and insure a secure mounting. Thereupon, the members 16 and 21, with the pipe 23 and the parts carried thereby, are moved upwardly beneath the member 10 with the arms or lugs 17, 18 and 19 in such position that they come beneath the parts 10^a, 10^b and 10^c. Then the member 16 is turned through a small angle relative to the member 10 to bring the lugs or arms 17, 18 and 19 over the parts 13^a, 14^a and 15^a.

After the parts have been assembled as above described, large headed screws 26 are threaded into one or more of the parts 10^a, 10^b and 10^c, from the bottom, and the heads of these screws prevent turning of the part 16 and hence prevent movement of the arms or lugs 17, 18 and 19 out of position upon the supporting surfaces 13^a, 14^a and 15^a.

The coacting rounded surfaces of the member 21 and the member 16 provide a ball and socket support which permits the pipe 23 to hang vertically irrespective of deviations from the horizontal plane in which the member 10 is secured. If the ceiling slants somewhat, or if the stud to which the part 10 is secured does not hang just vertically, the pipe 23 will still hang in a vertical position. Projecting outwardly from the upper edge of the member 21 is a lug 27 which enters a vertical slot 28 in the side of the cup-shaped member 16. This lug prevents any substantial relative turning between the parts 21 and 16, but sufficient clearance is allowed to permit the member 21 to swivel freely in the rounded interior of the member 16 so that the parts supported therefrom may hang vertically.

From the foregoing, it will be seen that the supporting fixture shown herein achieves many practical advantages. The parts supported will hang vertically without careful and accurate positioning of the fixture when it is secured to the ceiling. A strong connection may be made between the pipe 23 and the member 21 before the parts are lifted into position, and thereafter the remaining steps of the assembly are accomplished by simply a slight turning of the member 16. This latter feature, permitting assembly of the supporting fixture with very slight relative turning

of the parts is of distinct advantage, doing away with the danger of pulling apart the electrical connections during assembly and the danger of wearing off the insulation. The lead wires shown at 29 may be brought out between any two of the parts 10^a, 10^b and 10^c with the greatest convenience and without requiring any special outlet passage or device. When it is desired to take the fixture down, it is necessary merely to remove the screws 26 and give the part 16 a slight rotation to move the parts 17, 18 and 19 off the parts 13^a, 14^a and 15^a.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim as my invention:

1. In a supporting fixture for lamps or the like, in combination, a member adapted to be secured to a ceiling and having a plurality of depending supporting arms, said arms being shaped to provide upwardly facing supporting surfaces, a member fitting within said arms and having a plurality of outwardly extending lugs resting upon said supporting surfaces, said last member being removable from said first member by relative rotary movement between said members, said second-mentioned members being interiorly substantially cup-shaped and adapted thereby to form a socket, and a third member resting loosely within said cup-shaped member and within the compass of the depending arms of said first-mentioned member and having a rounded outer surface substantially seating within the socket portion of said second-mentioned member, and means adapted to secure a device to said third-mentioned member and adapted to depend therefrom.

2. In a supporting fixture for lamps or the like, in combination, a member adapted to be secured to a ceiling and having a plurality of substantially annularly arranged spaced depending L-shaped arms, the free ends of the horizontal portions of each being spaced from the vertical portion of an adjacent arm, a member hanging from said first member and having a plurality of laterally projecting lugs adapted to rest upon the horizontal portions of said L-shaped arms, a third member fitted within said second-mentioned member, said two members having coacting surfaces adapted to form substantially a ball and socket joint and said second-mentioned member having an opening therein through which a hanging device may be secured to said third-mentioned member, means for preventing said third-mentioned member from rotating about a horizontal axis relative to said second-mentioned member, and means con-

trollable at will for preventing said second-mentioned member from being rotated to swing said lugs thereon off of said horizontal portions of said L-shaped arms.

5 3. In a supporting fixture for lamps or the like, in combination, a member adapted to be secured to a ceiling and having annularly arranged spaced depending means thereon provided at their ends with laterally 10 extending horizontal arms, the said horizontal arms being adapted to provide a plurality of spaced supporting ledges, and a member hanging from said first member having a plurality of laterally projecting 15 lugs resting upon said supporting ledges, said second member being removable from said first member by rotating said second member and moving said lugs downwardly through the spaces between said spaced L-shaped 20 means, and a screw removably threaded into said member through the bottom thereof adjacent one of said ledges for coacting with one of said lugs and preventing said rotary movement.

25 In testimony whereof, I have signed my name to this specification this eighteenth day of June, 1927.

GEORGE E. HULSE.
